CLAIM

The ornamental design for a penetrating charge dispenser, as shown and described.

DESCRIPTION

FIG. 1 is a top perspective view of a penetrating charge dispenser.

FIG. 2 is a top view of the penetrating charge dispenser of FIG. 1.

FIG. 3 is a bottom view of the penetrating charge dispenser of FIG. 1.

FIG. 4 is a front view of the penetrating charge dispenser of FIG. 1.

FIG. 5 is a back view of the penetrating charge dispenser of FIG. 1.

FIG. 6 is a right side view of the penetrating charge dispenser of FIG. 1.

FIG. 7 is a left side view of the penetrating charge dispenser of FIG. 1; and,

FIG. 8 is a bottom perspective view of the penetrating charge dispenser of FIG. 1.

Broken lines in the Figures illustrate portions of the penetrating charge dispenser that form no part of the claimed design.

1 Claim, 4 Drawing Sheets
